UNITED STATES PATENT OFFICE.

SAMUEL F. BURNET, OF ST. LOUIS, MISSOURI, ASSIGNOR TO LACLEDE-CHRISTY CLAY PRODUCTS CO., OF ST. LOUIS, MISSOURI, A CORPORATION OF MISSOURI.

ARCH-NOSE CONSTRUCTION.

Application filed October 17, 1925. Serial No. 63,202.

This invention relates to improvements in arch nose construction, and has for its objects to provide an arch nose which may be readily removable; which will permit ready replacement of the tile thereof; which includes a supporting bracket or member as a novel article of manufacture; which insures proper positioning of the tile upon a supporting member and prevents accidental displacement therefrom after assembly; which includes a supporting means for the curtain wall, which will also properly position and prevent accidental displacement of the constituents thereof. These and other objects will be more fully set forth and described in the following specification as shown in the accompanying drawing, which is a vertical section of a portion through the fire arch, the nose supporting bracket being shown in elevation.

In the drawing, 10 indicates generally a portion of a hanger of a fire arch having a bottom tile engaging or supporting flange 10^a, upon which are mounted conventional refractory tile 11 as clearly shown. A transverse supporting beam 12 is provided to which is bolted one end of the hanger 10. Bolted to the opposite side of the beam 12 is my novel nose supporting bracket 13, having the vertical flange 13^a bearing against and secured to the web of the beam 12. Surrounding the periphery of the nose bracket 13 is flange 13^b of sufficient width at the top to provide a support for the refractory brick or tile 14 of the curtain wall, an upwardly projecting rib 13^c being provided to position and prevent accidental displacement of the curtain wall tile. Depending from the bracket 13 is a flange 13^d provided at its lower edge with a tile engaging or supporting edge 13^e, upon which additional tile 11 are mounted to form a continuation of the flat portion of the arch. Located above and at one side of the flange 13^e is a substantially horizontal flange 13^f projecting outwardly from the bracket 13 connected thereto by means of a web 13^g. Adjacent the flange 13^f the continuous flange 13^b is provided with a vertical portion 13^h, which functions as a stop member, as will be described. Located above and outwardly of the flange 13^f, which I term the intermediate flange, is the upper flange 13ⁱ inclined upwardly and out-

wardly from the bracket 13, and also connected thereto by the triangular web 13^k. The continuous flange 13^b above and adjacent the flange 13ⁱ is also provided with a vertical portion 13^m, functioning as a stop flange.

In the construction of the arch nose the tile 15, having a flange engaging recess 15^a, is mounted upon the bracket flange 13^f in the manner shown in the drawing, the stop portion 13^m of flange 13^b serving to limit the insertion movement of the block or tile 15. The block 15 is provided with the outwardly diverging surfaces 15^b and 15^c and the rounded surface 15^d.

A second irregularly shaped block or tile 16 is provided having a blind end recess 16^a, which is mounted upon the inclined supporting flange 13ⁱ but limited also in its attaching movement by the stop portion 13^m of flange 13^b. The tile 16 has an outwardly inclined lower surface 16^b and a horizontal upper surface 16^c, being rounded at the lower portion of its outer surface 16^d to form a smooth continuation of the arch nose. The upper surface 16^c of block 16 is spaced from the lower brick 14 of the curtain wall, and to fill this space an ordinary fire brick 17 is inserted, which also serves to prevent upward movement of the block or tile 16, which would be necessary to displace it from the inclined flange 13ⁱ, whereby it will be seen that accidental displacement of the tile 16 is prevented and it in turn prevents accidental displacement of the tile or block 15, which in turn retains the tile 11 against such displacement.

It will be apparent that with an arch nose constructed as shown and described the component refractory tile members are individually and separately supported in such wise that there is substantially no torque or turning movement about the supports, since each of said supports is substantially horizontal. This eliminates a stress found in other types of arch detrimental to the tile. Also proper arrangement of the stop members relative to the flanges as well as properly dimensioned and constructed tile are incorporated to properly space the tile when cool to accommodate the necessary expansion when heated, thereby eliminating crushing resistance or compression between the respective tile. Also by

raising or vertically spacing the supporting flanges a greater depth of refractory will be found at the nose portion, whereby it is desired to interpose greater resistance to the intense heat there encountered.

It will be obvious that my nose bracket 13 may be readily cast as an article of manufacture and provides a separate support for the different types of tile or blocks making up the 10 arch nose. Also as explained above, the component members of the arch nose are prevented from accidental displacement in view of the construction and arrangement described. The curtain wall is also readily positioned 15 and retained against lateral displacement, being also wholly and independently supported by the arch nose bracket and not upon the tile of the arch nose.

I do not wish to be restricted to the form 20 of my invention shown and described except as defined in the appended claims.

What I claim is:

1. An arch nose supporting member having a lower horizontal tile supporting flange, 25 an intermediate tile supporting flange extending outwardly from said member, and an upper tile supporting flange extending outwardly and upwardly from said member, said upper flange partially overlying and located 30 above and projecting beyond said intermediate flange, said flanges being open at their outer ends and constructed and arranged to permit sliding movement of tile into position on said flanges.

35 2. An arch nose comprising a supporting member having supporting flanges spaced laterally and vertically from each other, stop members co-acting therewith, refractory tile recessed for engagement with and separately supported by said flanges and contacting with said stop members when in assembled relation, said stop members being located and said tile constructed to provide the desired clearance between adjacent tile.

45 3. An arch nose comprising a supporting member, said supporting member being provided with a supporting flange at its lower portion, and a second tile supporting flange located above and at one side of said first named flange, said second flange being inclined outwardly and upwardly from said member, a refractory block mounted upon said first named flange and having its upper face inclined outwardly and downwardly 50 from said member, a second tile mounted upon said second flange, said last named tile having a lower face adjacent the inclined face of said first named tile, and a substantially horizontal upper face with means co-acting with said upper face to lock said tile against accidental displacement from said supporting member.

60 4. An article of manufacture comprising an integral arch nose bracket formed with a curtain wall supporting flange and a plural-

ity of outwardly projecting spaced tile supporting flanges, one of said flanges being inclined upwardly and outwardly from said bracket, said bracket being further provided with a stop flange coacting with each of said 70 outwardly projecting flanges to limit the movement of insertion of each of said tile.

5. An arch nose supporting member having an outwardly projecting tile supporting flange, a second tile supporting flange partially overlying said first named flange being spaced from and located above said first named flange and projecting therebeyond, said second named flange extending outwardly and upwardly from said member, both 75 said flanges being open at their outer ends and constructed and arranged to permit sliding movement of refractory tile into position on said flanges.

6. An arch nose comprising a supporting 80 member having a lower tile supporting flange and a second tile supporting flange partially overlying said first flange being spaced from and projecting beyond said first flange, a lower nose tile carried by said lower flange, 85 and an upper nose tile carried by said upper flange and partially overlying said first tile.

7. An arch nose comprising a supporting member having a lower tile supporting flange and a second tile supporting flange partially 90 overlying said first flange being spaced from and projecting beyond said first flange, said second flange being also inclined upwardly from said member, a lower nose tile carried by said lower flange, and an upper nose tile 95 carried by said upper flange and partially overlying said first tile.

8. An article of manufacture comprising an integral arch nose bracket formed with a curtain wall supporting table portion and a 100 plurality of underlying spaced tile supporting flanges located one above the other and constructed for the free insertion of slotted refractory tile, one of said flanges partially overlying the subjacent flange.

9. An article of manufacture comprising an integral arch nose bracket formed with a curtain wall supporting table portion and a plurality of underlying spaced tile supporting flanges located one above the other and 110 constructed for the free insertion of slotted refractory tile, one of said flanges partially overlying the subjacent flange, said overlying flange being also inclined upwardly and outwardly from said bracket.

10. An article of manufacture comprising an integral arch nose bracket formed with a curtain wall supporting table portion, a plurality of outwardly projecting tile supporting flanges, one of said flanges partially overlying a subjacent flange, and stop means associated with said overlying and subjacent flanges to limit the entering movement of refractory tile.

11. An arch nose comprising a supporting 120

member, said member being provided with a plurality of tile supporting flanges open at their outer ends, one of said flanges partially overlying the subjacent flange, a stop flange 5 associated with said overlying and subjacent flanges, and refractory slotted tile slidable longitudinally into position on each of said flanges, each of said tile being limited in its

positioning movement by said stop flange and being separately and wholly supported on 10 said flange, and further being formed on its outer surface to form a nose of desired conformation.

In witness whereof, I hereunto subscribe my name to this specification.

SAMUEL F. BURNET.
